Primary Examiner — Brian N. Vinson(74) *Attorney, Agent, or Firm* — Hamre, Schumann, Mueller & Larson, P.C.(57) **CLAIM**

The ornamental design for a lens for a light projector, as shown and described.

DESCRIPTION

FIG. 1 is a perspective view of the projector light device shown for environmental purposes only.

FIG. 2 is a perspective view of a condensing lens.

FIG. 3 is a front view of FIG. 2 thereof.

FIG. 4 is a top view of FIG. 2 thereof.

FIG. 5 is a bottom view of FIG. 2 thereof; and,

FIG. 6 is a bottom view of FIG. 2 shown in cross section taken along lines 6-6 of FIG. 4 to more clearly show the interior recess.

The broken line disclosure represents the lighting head which form no part of the claimed design.
